UNITED STATES PATENT OFFICE.

WALTER E. LUMMUS, OF LYNN, MASSACHUSETTS.

METHOD OF REFINING PETROLEUM.

Application filed May 21, 1923. Serial No. 640,332.

The present invention relates to an improved method of refining petroleum oils. The lower boiling mixed petroleum vapors are difficult or impractical to condense completely by usual methods and some of them are customarily lost in petroleum refining and in the recovery of oils from natural gas. Such vapors usually consist of mixtures of hydrocarbons having boiling or condensing points ranging from 800° F. to 0° F. at atmospheric pressure and therefore contain vapors that alone would be uncondensable without refrigeration or pressure, or both. In refining petroleum oils by distillation, the vapors from the stills are liquefied by passing them through one or more water-cooled condensers, usually consisting of a coil or coils of pipe of considerable aggregate length. This process of cooling and condensing affects first those portions of the mixture that are most easily condensed, then the surviving vapors that are less readily condensed, and so on, with the result that the fractions having lowest boiling or condensing points and which are usually the most valuable, tend to concentrate and survive as vapor that is uncondensable at the temperatures and pressures employed in the condenser, and therefore escape and are lost. The value of some of these so-called uncondensable vapors is sometimes so great that their recovery, by economical means, would add materially to the profit or lower the cost of all the products of the operation with which they are concerned.

The principal object of the invention is to recover the more reluctantly condensable vapors resulting from the distillation of petroleum oils. Casing head oils are condensed from gases and vapors by a process involving the use of compression and refrigeration, and the products contain highly volatile oils or light vapors which are reluctantly condensable. Such vapors are lost when the pressure is reduced, or they are lost when the oils are mixed with warmer oils, inasmuch as they have low boiling points and tend to evaporate from the mixture. The loss is due not alone to the escape of such light vapors or low boiling oils, but in their escape from the mixture they carry off with them certain quantities of higher boiling oils which increase the losses due to their evaporation.

Another object of the invention is to produce a method of refining petroleum oils by virtue of which the light vapors of low boiling oils are condensed, absorbed or dissolved in higher boiling oils of such character as to retain them in solution or absorbed or liquefied condition.

Other objects of the invention will be apparent from the following description of the method, which consists in the process of refining petroleum oils hereinafter described and particularly defined in the claims.

In the accompanying drawings Fig. 1 illustrates a petroleum oil distilling apparatus of the continuous type for practicing the method of the present invention; Figs. 2, 3 and 4 illustrate other forms of apparatus by means of which the invention may be practiced.

Referring to Fig. 1, the still 10 is heated by a furnace 11 controlled by a valve 12 and discharges its vapors through the vapor pipe 13 to the bottom of a distilling column or contact path apparatus 14 from which the effluent vapors pass through the vapor pipe 15 to the condenser. The return pipe 16 permits any liquid collecting in the bottom of the column to return to the still. The still is provided with an overflow pipe 17. The vapors effluent from the distilling column 14 are introduced into the cooling zone of a condenser 18 where a portion of the vapor is condensed and flows out into the bottle 19 from which a portion of the condensate flows through the pipe 20 to pieces of apparatus hereinafter referred to. The condensate flowing from the condenser 18 comprises as its principal ingredient the more readily condensable vapor constituents of the vapors effluent from the column 14. A second portion of this same condensate flows through the pipes 21 and 22 to the top of the column 14. The petroleum oil mixture which is introduced to the apparatus is preheated by passing through the condenser 18. It is introduced through the oil pipe 23 and passes through the condenser and flows through the pipe 24 to an intermediate chamber of the column 14. As shown, the oil may be introduced at any one of three compartments of the column. This apparatus is continuous and in operation, oil flows in through the oil pipe to the column where it is divided into two

effluents, a vapor effluent, which passes out through the vapor pipe 15, and a liquid effluent, which passes out through the vapor pipe 16 to the still, from which latter the liquid effluent from the column finally finds its way out of the apparatus. The uncondensed vapors from the condenser 18 pass through the vapor pipe 25 to the cooling zone of a condenser 26 cooled by a stream 5 of water entering through the pipe 27 and passing out through the pipe 28. In this condenser 26 a further portion of the effluent vapors of the column is condensed and the condensate passes into the bottle 29 along with a certain last portion of the effluent vapors from the column which passes out of the second condenser 26 uncondensed. These are the more reluctantly 10 condensable vapors effluent from the column. A portion of the condensate from the condenser 26 flows through the pipe 30 and is discharged as a second condensate product. A second portion of the condensate from the second condenser 26 flows 15 into the pipe 22 and is returned to the top of the column therethrough. The effluent uncondensed vapors from the second condenser 26 pass through the vapor pipe 31 to the column scrubber 32, being introduced 20 at the bottom of this scrubber. A portion of the condensate from the first condenser 18 passes through the pipe 20 to the cooler 33 from which it is discharged into the bottle 34 from which a portion is discharged 25 as first distillate through the pipe 35. A second portion of this first distillate is led through the pipe 36 to the top of the column scrubber 32 where it trickles down through the scrubber and absorbs, dissolves 30 or condenses the more reluctantly condensable vapors flowing into the bottom of the scrubber. The scrubber discharges through the pipe 37 a product which consists of the condensed, absorbed or dissolved vapors entering the scrubber from the second condenser contained in the liquid effluent from the non-adjacent condenser 18, i. e., the non-adjacent fractional condensate from the 35 first condenser.

50 The apparatus thus described operates on the vapor flowing from the distilling column and condenses it in a plurality of steps. The condensate with the apparatus shown is thus divided into two portions, which may be referred to as a No. 1 distillate from the 55 first condenser and a No. 2 distillate from the second condenser. The third product which may be called No. 3 distillate consists of No. 1 distillate to which has been added the reluctantly condensable vapors effluent from the last condenser. The whole vapor effluent from the column, for example, may be regarded as gasoline, and No. 1 distillate would have a certain boiling point, No. 2 distillate 60 would have a slightly higher boiling point, 65

and No. 3 distillate might have a boiling point the same as No. 2 distillate.

The separation of the three products is of no significance. The object of the method is to liquefy the lighter effluent vapors from the distilling column, and in order to condense, absorb or dissolve such more reluctantly condensable vapors it is necessary, according to the present invention, to subject them to the absorbing, dissolving or condensing action of a distillate non-adjacent thereto. In my prior Patent No. 1,336,-360, the more reluctantly condensable materials comprised in the vapor substance introduced into the condenser were subjected to the absorbing action of the entire liquid effluent from the condenser. The method of that patent was particularly intended for use in treating vapors present in coke oven gases such as benzol toluol and associated high boiling oils, each of which has a distinct precise boiling point. It was also adapted for use in liquefying ether, carbon disulphide and other volatile liquids from a vapor state either alone or mixed with non-condensable gases. While the present method is one embodiment or form of the method of said patent, it has been found that in treating petroleum oils a non-adjacent condensate is more efficient in condensing, dissolving or absorbing the more reluctantly condensable portion of the vapors. In fact, the more remote the condensate or the higher its boiling point, the greater its capacity to absorb, dissolve or condense the more reluctantly condensable vapors. In the former patent, therefore, the vapor substance admitted was in part condensed, and the uncondensed portion was treated by the condensed portion and specifically by the condensate of the identical substance, whereas in the present invention the more reluctantly condensable vapors contained in the vapor substance admitted to the condensers are subjected to the absorbing, dissolving or condensing action of non-adjacent fractional condensates of such vapor of higher boiling point.

The important feature of the invention resides in the increased recovery of the reluctantly condensable vapors by dissolving, condensing or absorbing them in a non-adjacent condensate from which such vapors have been separated.

It is to be observed that the saving of the more reluctantly condensable vapors is effected by introducing them into and uniting them with a product or a substance which, when it shall have absorbed such lighter oil vapors, will constitute a final product, and so far as the invention, viewed in its broader aspects, is concerned, it is immaterial if all three of the distillate products of this apparatus are discharged into a common receptacle, this product being increased in amount by the recovery of the more re-

luctantly condensable vapors of the original distillate, which, in fact, are the most valuable condensates of such distillate.

In the apparatus illustrated in Fig. 2 there are three condensers 50, 51 and 52 employed. The uncondensed gas or vapor from the last condenser is conducted by means of the pipe 53 to the column scrubber 54 where it is subjected to the absorbing, condensing and dissolving action of a mixture of the non-adjacent condensates from condensers 50 and 51. By the use of the cocks in the condensate pipes from the condensers 50 and 51, the condensate from either of these condensers may be employed in the scrubber or their mixture in any proportions desired, a portion of each being returned to the column 14 as before. The condensate of the first condenser is discharged at 55, that from the second condenser at 56 and that from the third condenser at 57 and that from the column scrubber at 58.

If it is desired to use the more remote condensate for dissolving, absorbing or condensing the more reluctantly condensable vapors of the vapor mixture effluent from the column 14, then the cock in the condensate pipe from the condenser 51 will be closed and the condensate from the condenser 50 will be employed in the scrubber. Again, the condensate from the condenser 51 only may be used, and the condensate of the most remote condenser may be drawn off at 55. Again, a certain portion of the condensate from the condenser 50 and 51 may be used, more of one than the other if desired, and parts of these condensates drawn off as separate products.

The characteristic feature of the specific method susceptible of being practiced by the apparatus of Fig. 2 is the recovery of the more reluctantly condensable vapors in a mixture of non-adjacent condensates.

In the apparatus of Fig. 3 which is employed in practicing still another specific modification of the process, three condensers 60, 61 and 62 are employed, and the vapor from the last condenser is conducted by means of the pipe 63 to the column scrubber 64 where the vapors are subjected to the scrubbing action of the condensate of the next lower condenser. From this scrubber any uncondensed vapors are conducted by means of the pipe 65 to the second column scrubber 66, where they are subjected to the scrubbing action of a condensate from the condenser 60. In this method the recovery is accomplished in progressive fashion, the more reluctantly condensable vapors being condensed, absorbed or dissolved in the more remotely non-adjacent condensates.

In the apparatus illustrated in Fig. 4 still another specific mode of practicing the present invention is diagrammatically illustrated. Here the vapors effluent from the

distilling column or contact path apparatus 14 are conveyed through the vapor pipe 70 to the condenser 71. In this condenser a portion of the vapors are condensed and returned by the reflux pipe 72 to the top of the contact path apparatus 14. A cooling fluid is introduced into this condenser through the pipe 73 and flows out through the pipe 74. The uncondensed vapors from the condenser 71 flow through the vapor pipe 75 to the bottom of a second distilling column or contact path apparatus 76. Here the vapors rise and condensates descend through the apparatus 76 and flow out through the liquid effluent pipe 77. These liquid effluents are cooled in the cooler 78 for use in a column scrubber. The vapor effluent from the contact path apparatus 76 is conducted through the vapor pipe 80 to the condenser 81 where a portion of the vapors is condensed, part being discharged at 82 as a liquid product, and part returned through the reflux pipe 83 to the top of the contact path apparatus 76. The uncondensed vapor effluent from the condenser 81 is carried by the pipe 84 to the second condenser 85 where a further portion of the vapors is condensed and discharged at 86. The remaining vapors uncondensed by the second condenser 85 are conducted by the vapor pipe 87 to the column scrubber 88, where they are subjected to the scrubbing action of the condensate effluent from the contact path apparatus 76 above referred to, which has previously been cooled in the cooler 78 and is now conducted by a pipe 89 to the top of the column scrubber 88. In this column scrubber the vapors effluent from the second condenser are subjected to the dissolving, condensing and absorbing action of the remote condensate, and the resulting product is discharged at 90.

Here it will be seen that the original vapor substance effluent from the still 10 is divided into two portions by means of the contact path apparatus 14 and the reflux condenser 71. The vapor from this apparatus is again divided in the contact path apparatus 76 into two portions, the high boiling portion being discharged as a liquid effluent through the cooler to the top of the column scrubber 88, and the low boiling portion being discharged as a vapor effluent from the contact path apparatus 76, and the reluctantly condensable portions thereof being recovered by being absorbed, dissolved or condensed in the high boiling portion of the same original vapor substance.

While some of the vapors herein referred to as such may partake of the nature of gases, it is to be understood that the expressions "vapor" and "vapors" as used in this specification and the claims are intended to describe effluent vapors and gases.

The expression "higher boiling condensate

fraction" or the like, used in some of the claims, is obviously meant to exclude the lowest boiling of the condensate fractions obtained prior to the absorbing action.

5 Having thus described the invention, what is claimed is:

1. The method of refining petroleum oils which comprises vaporizing said oils, passing the vapors through a plurality of condensers for condensing them into a plurality of condensates of different boiling points and an uncondensed vapor fraction, and passing said uncondensed vapor fraction and certain of the higher boiling of said several 15 condensates other than the lowest boiling of said condensates in counter-current contact.

2. The method of refining petroleum oils by separating the heavier oils from the 20 lighter and passing the vapors of the latter through a plurality of condensers which condense and discharge condensate fractions of the vapors of different boiling points, and subjecting the uncondensed vapors 25 from the last condenser to the absorbing action of a higher boiling of said condensate fractions.

3. The method of refining petroleum oils by separating the heavier oils from the 30 lighter and passing the vapors of the latter through a plurality of condensers, which condense and discharge condensate fractions of the vapors of different boiling points, and subjecting the uncondensed vapors from the 35 last condenser to the absorbing action of a mixture of the higher boiling of said condensate fractions.

4. The method of refining petroleum oils by separating the heavier oils from the 40 lighter and passing the vapors of the latter through a plurality of condensers, which condense and discharge condensate fractions of the vapors of different boiling points, subjecting the uncondensed vapors from the

last condenser to the absorbing action of one 45 of the higher boiling of said condensate fractions, and subjecting the uncondensed vapors remaining to the absorbing action of a still higher boiling condensate fraction.

5. The method of refining petroleum oils 50 by separating the heavier oils from the lighter and passing the vapors of the latter through a plurality of condensers, which condense and discharge condensate fractions of the vapors of different boiling 55 points, and subjecting the uncondensed vapors from the last condenser to the absorbing action of the higher boiling of said condensate fractions in succession from condensates of lower boiling point to those of 60 higher boiling point.

6. The method of refining petroleum oils which consists in first separating the heavier oils from the lighter oils, and in then subjecting the vapors of the latter to the action 65 of a contact path apparatus to effect a separation from such vapors of the high boiling constituents as a liquid, cooling the same, passing the vapor constituents through a series of condensers to form a plurality of 70 condensates of different boiling points, and subjecting the uncondensed vapors from the last condenser to the absorbing action of the higher boiling of said condensates.

7. The method of liquefying gas-vapor 75 mixtures consisting in passing a stream of the mixtures through a series of cooling zones to liquefy in each a portion of the mixtures, withdrawing from said zones in separate streams the several liquefied portions of said mixtures, and subjecting the uncondensed effluent of the last cooling zone to the absorbing action of the liquid effluent from a non-adjacent cooling zone to absorb, 80 dissolve or condense a further portion of the 85 initial gas-vapor mixture.

WALTER E. LUMMUS.
